UNITED STATES PATENT OFFICE.

WILLIAM M. WILKIN, OF ERIE, PENNSYLVANIA.

BAND-SAW MILL.

SPECIFICATION forming part of Letters Patent No. 406,322, dated July 2, 1889.

Application filed December 17, 1888. Serial No. 293,865. (No model.)

To all whom it may concern:

Be it known that I, WILLIAM M. WILKIN, a citizen of the United States, residing at Erie, in the county of Erie and State of Pennsylvania, have invented certain new and useful Improvements in Band-Saw Mills; and I do hereby declare the following to be a full, clear, and exact description of the invention, such as will enable others skilled in the art to which it appertains to make and use the same.

This invention relates to band-saw mills; and it consists in the improvements in the construction thereof, as will be hereinafter fully described, and pointed out in the specification and claims.

The invention is illustrated in the accompanying drawings, as follows:

Figure 1 is an elevation view looking in the direction of the travel of the log-carriage. Fig. 2 is an elevation view looking across the line of traverse of the log-carriage. Fig. 3 shows details of construction which will be explained in place. Fig. 4 is a vertical sectional view of a part of the frame-work, taken on the line $x-x$ in Fig. 1. Fig. 5 is a horizontal sectional view of the cross-arm A^3 of the frame-work, taken on the line $y-y$ in Fig. 1, and shows the internal construction of the adjusting mechanism. Fig. 6 is a vertical section of a fragment of the frame-work, taken on the line $z-z$ in Fig. 5. Fig. 7 is a vertical section of the same fragment, taken transversely of the arm A^3 on the line $w-w$ in Fig. 6, with the internal works in elevation. Figs. 8, 9, 10, 11, 12, and 13 are similar to Figs. 5, 6, and 7, and show alternative construction of the adjusting mechanism.

The construction is as follows, reference being had to the letters of reference marked on the drawings. There is the common supporting frame-work A and base-plate A', or "husk," as it is commonly called. Mounted on the husk is a T-shaped column $A^2 A^3$, of which A^2 is the shaft and A^3 the cross-arm. On this cross-arm are mounted two hollow posts $A^4 A^4$, and from the outer end of the cross-arm there depends a hanger A^5 , which supports the outer end of the lower band-wheel shaft. This outer hanger is not an essential feature, for, if desired, an inner bearing can be used which will support the end of the shaft. An outer bearing is, however,

preferable. In the top of the posts $A^4 A^4$ are telescopically fitted bearing-posts D D, which carry journal-boxes D' D', which are pivoted at d , so as to tip in the plane of the shaft which they support. These telescoping studs are supported on screw-shafts G, which have worm-wheels g thereon, which gear into worms on the shaft I.

B is the lower or driving band-wheel, which is mounted on a shaft b, which has its outer bearing in the hanger A^5 .

B' is the upper or driven band-wheel, which is mounted on the shaft b', which has its bearings in the journal-boxes D' above described. On the cross-arm A^3 , just inside of the band-wheel B', is erected a post and arm E, which carries the saw-guide E² and its actuating mechanism, which will be explained further on.

The inner bearings of the driving band-wheel shaft b are secured to the under side of the husk. One of these bearings or supports is marked A⁶, and is shown in detail in Fig. 3. Its peculiarity consists in the manner in which it holds the journal-boxes a' a' between guide-lips a² a², so that the boxes have free vertical action, thus allowing vertical adjustment of the shaft, but holding it against lateral vibration.

In Fig. 1 I show an arm K, extending from the post E back to the saw at the point where it is about passing on the driven pulley B'. This arm carries a roller K', which runs upon the back of the saw and serves to keep the saw in place on the driven pulley. Heretofore it has been common to apply a roller to the back of the saw at about the point where it leaves the upper band-wheel, and great difficulty has been experienced in obtaining any beneficial result from them. I have found that by placing this roller at about the point where the saw runs upon the upper band-wheel the desired effects are perfectly accomplished.

Constructing the upper frame-work in the manner I do, as shown, I find to be a very great improvement. It will be observed that there is no large mass of metal above the point where the saw does its work, the cross-arm A^3 being in the same horizontal plane as the log to be sawed, and the frame-work above it being very light and yet very strong. The

shaft A^2 , which supports the cross-arm, has a very wide firm base, and it thoroughly braces the cross-arm against any lateral strain. The cross-arm A^3 and the shaft A^2 are cast in one piece, or, preferably, should be, and this gives a firm support for the outer post A^4 and the outer hanger A^5 , which form the outer supports of the two shafts b and b' . The entire vertical adjustment of the upper wheel is effected by the screw-shafts G and their supports. The adjustment of the upper wheel to the length of the saw is effected by turning the shaft I , which revolves the screw-shafts G simultaneously. When this adjustment is properly effected, the proper tension upon the saw is maintained by weights acting upon levers, which carry the supports of the screws G , this in effect sustaining the upper band-wheel flexibly on scale-beams. Broadly, it is not new to so support either one or both ends of the upper wheel-shaft, as will be seen by examining the following Letters Patent of the United States: No. 120,949, dated November 14, 1871, No. 151,106, May 19, 1874, No. 194,225, August 14, 1877, No. 278,933, June 5, 1883, No. 301,095, July 1, 1884, No. 368,731, August 23, 1887, and No. 369,881, September 13, 1887, my invention in this particular consisting in the construction and arrangement of the parts by which I effect the desired result.

In the accompanying drawings I show several alternative constructions of scale-gearing for flexibly supporting the upper band-wheel shaft, which are equivalents of each other and will be explained in place farther on.

The essential feature of the apparatus is that the upper band-wheel and mechanism by which it is adjusted with reference to the length of the saw are supported flexibly on an automatic tension device. Broadly, this is not new, as it is done in band-saws used for scroll sawing; but the constructions there used are inapplicable to large saw-mills of the class to which my invention relates, and heretofore large mills have been made with the tension mechanism vertically adjustable with and supported on the upper band-wheel supporting frame-work. My construction in this particular is as follows:

The frame-work $A^2 A^3 A^4 A^5$ is fixed and immovable, but the posts $A^4 A^5$ are made extensible by having telescoping parts D which slide within or upon said posts vertically. These telescoping posts are adapted to receive the boxes of the shaft b' , and they are moved vertically by screw-shafts G , which are revolved simultaneously by a worm-shaft I and worm-wheels g . These screw-shafts move the telescoping parts D and the shaft supported thereon to effect the vertical adjustment necessary to accommodate saws of various lengths, and they have their supports on a scale-gear, which gives them automatic vertical adjustment in parallelism, so as to give proper tension upon the saw. When it is desired to tilt the shaft b' , so as to properly train the saw on the wheel B' , it may be effected by throwing

one of the worm-wheels I' on the shaft I out of gear with the worm-wheel g , as is shown by dotted lines in Fig. 5, or in any other manner which will be efficient.

The automatic tension giving support for the screw-shafts may be variously constructed, and I do not desire to be limited to any particular construction. In the accompanying drawings I show it constructed as follows: A rock-shaft H extends from end to end of the cross-arm A^3 , and has arms $H' H'$ extending from it, on which rests the ends of the screw-shafts G . In the construction shown in Figs. 5, 6, and 7 one of these arms H' is extended, and rests upon a second lever H^2 , which is connected with a weight-lever H^3 by a link h . In the construction shown in Figs. 8, 9, and 10 one of the arms H' is extended and connects directly with the weight-lever H^3 by the link h . In the construction shown in Figs. 11, 12, and 13 there is a separate arm H^4 extending from the shaft H , and this is connected with the weight-lever H^3 by the link h . These modifications are practically alike, but go to show that many modifications are possible.

The saw-guide E^2 is in the form of an arm, which extends from a sliding bar E^3 , which slides in the head E' on the arm E . The means for moving this slide is a screw F , which is journaled in a bracket E^4 on the arm E back of the head E' , which screws into a nut e^3 on the back of the slide E^3 . The screw F has a beveled pinion f below its journal, and a pinion f' on the shaft F' meshes with it. On the opposite end of the shaft F' is another beveled gear f^2 , which gears with a like gear f^3 on the upright shaft F^2 . On the lower end of the shaft F^2 there is a friction-gear f^4 , which engages with a like friction-gear on the horizontal shaft F^3 . A lever F^5 is provided for moving the shaft F^2 , so as to bring the friction-gear f^4 in contact with one or the other of the friction-gears on the shaft F^3 . The shaft F^3 is the shaft used for driving a clearance-roller R , commonly used.

Referring again to the construction of the frame, I will say that it is not essential that the cross-arm A^3 extend back of the shaft A^2 and form a T , strictly, for if it is desired the shaft A^2 may be coextensive in depth with the part A^3 . The essential feature of this construction is that the part A^3 extends out between the two wheels B and B' and forms a support for an outer post A^4 , and a support also for the leg A^5 when that part is wanted. I am aware that the outer end of the upper shaft b' has been supported by an arm, or, as it is called by some, a "goose-neck," extending from the column out under the upper wheel and up to the shaft, and I do not intend to claim such a construction.

The distinction between my construction and others is that in them the outer support of the upper band-wheel moves vertically with the wheel, while in my construction it is fixed, being supported by the fixed arm A^3 .

What I claim as new is—

1. In a band-saw mill, the combination, with the supporting frame-work and husk or bed and the upper and lower band-wheels and shafts, of a T-shaped column A² A³, which is mounted on said bed or husk and has one of its arms extended out between the two band-wheels in position to sustain the supports of the outer ends of the band-wheel shafts.
- 10 2. In a band-saw-mill frame, the combination, with the base A', of a fixed column composed of the shaft A² and the cross-arm A³, seated on said base, the outer hanger of the lower band-wheel depending from the lower 15 side of the outer end of said cross-arm, and the posts which support the upper band-wheel mounted at the ends of said cross-arm.
- 20 3. In a band-saw-mill frame, a column formed of the shaft A² and cross-arm A³, cast in one piece, in combination with the posts A⁴, mounted at each end of said cross-arm, and the hanger A⁵, suspended from the lower side of the outer end of said cross-arm.
- 25 4. In a band-saw-mill frame, the combination, with the T-shaped column A² A³, of the posts A⁴ A⁴, mounted on the ends of the cross-arm A³, and the guide post and arm E, mounted also on the cross-arm of said column between said posts A⁴ A⁴.
5. In a band-saw-mill frame, the combination of a base-support A, a base A', a T-shaped column A² A³, mounted on said base, an outer hanger A⁵, depending from the cross-arm of said column, a shaft b, supported at its outer end by the said hanger A⁵ and at its inner 35 end by a hanger depending from said base A', and held against lateral vibration by a hanger A⁶, having ways a², for vertically moving boxes a', said hanger A⁶ being between the outer hanger A⁵ and the driving-pulley on said 40 shaft and attached to said base.
6. In a band-saw mill, the combination of a fixed cross-arm extending out between the upper and lower band-wheels, a hanger A⁵ on the outer end of said cross-arm, for supporting the outer end of the lower band-wheel shaft, and extensible supports for the upper band-wheel shaft mounted on the ends of said cross-arm.

In testimony whereof I affix my signature in 50 presence of two witnesses.

WILLIAM M. WILKIN.
